UNITED STATES PATENT OFFICE.

ARETUS E. BLACK AND ROBERT ENGLISH, OF MARLETTE, MICHIGAN.

SAFETY-PLATE FOR RAILROAD-SWITCHES.

SPECIFICATION forming part of Letters Patent No. 276,554, dated May 1, 1883.

Application filed December 9, 1882. (No model.)

To all whom it may concern:

Be it known that we, ARETUS E. BLACK and ROBERT ENGLISH, citizens of the United States, residing at Marlette, in the county of Sanilac and State of Michigan, have invented a new and useful Safety-Plate for Railroad-Switches, of which the following is a specification, reference being had to the accompanying drawings.

This invention relates to safety-plates for railroad-switches, and has for its object to prevent such accidents as now frequently occur by persons having their feet caught in the frogs or switch-rails, and being unable to disengage or extricate themselves in time to avoid being maimed or killed by approaching trains.

To this end our invention consists essentially of plates fitted in or between the switch-rails and frogs level with the heads of the rails, and mounted upon springs sufficiently strong to support the weight of an ordinary person, but light enough to yield easily under the pressure of the wheels of cars passing over said plates, as will be hereinafter more fully described, and particularly pointed out in the claim.

In the drawings hereto annexed, Figure 1 is a plan view of a section of a railroad-track equipped with our improved safety-plates.

Fig. 2 is a section on the line *xx* in Fig. 1, and Fig. 3 is a section on the line *yy* in Fig. 1.

The same letters refer to the same parts in the several figures of the drawings.

A A in the drawings represent the main-line rails, B B the guard-rails, C C the frog-rails, and D D the wedge-rail of the frog. Between the sleepers, and under the rails herein shown are fitted boxes E E, which contain suitably-mounted springs, F F, which may either be flat or coiled, both of which constructions have been shown in the drawings; or they may be of any other suitable construction. G G represent flat plates, made preferably of steel, of any suitable dimensions in regard to thickness, and of such size and shape as to fit nicely between the main rails and guard-rails, at the ends of the latter, and be-

tween the frog-rails and wedge-rail, as shown. Said plates are provided with downward-projecting brackets B², to which are hinged rods or arms H H, extending into the boxes E, which are provided with hangers or brackets, to guide the said rods vertically. The rods H are provided near their lower ends with collars or flanges I, engaging or resting upon the springs, by which the plates G are thus supported. It is obvious that the springs are to be so adjusted as to support the plates G on a level with the heads of the rails; and they may be adjusted to yield at any desired pressure—say one hundred and fifty or two hundred pounds. The plates G are provided at their ends with hinged guard-plates J J, which hang down loosely, as shown, and rest upon the sleepers or upon the boxes E. The function of these plates is twofold—viz., first, to prevent the feet of persons from being caught under the ends of the plates G, and, second, to cause the wheels of passing trains to depress the plates G gradually and without any sudden shock, which might be injurious to said plates.

The operation and advantages of our invention will be readily understood. It is simple, inexpensive, easily applied, and thoroughly effective for the purposes stated.

We claim as our invention and desire to secure by Letters Patent of the United States—

The combination of the track-rails, the boxes fitted underneath the same, the guide-brackets or hangers, the springs contained in said boxes, and the safety-plates having hinged guard-plates, and provided with downward-projecting rods having flanges or collars engaging or resting upon said springs, all arranged and operating substantially as set forth.

In testimony that we claim the foregoing as our own we have hereto affixed our signatures in presence of two witnesses.

ARETUS E. BLACK.
ROBERT ENGLISH.
